US00D381512S

United States Patent [19]

Green

[11] Patent Number: Des. 381,512

[45] Date of Patent: **Jul. 29, 1997

[54] STORAGE CONTAINER

[75] Inventor: Patrick M. Green, Maryville, Tenn.

[73] Assignee: Rubbermaid Office Products Inc., Maryville, Tenn.

[**] Term: 14 Years

[21] Appl. No.: 47,472

[22] Filed: Dec. 5, 1995

[51] LOC (6) Cl. 03-01

[52] U.S. Cl. D3/294; D3/273; D9/424

[58] Field of Search D9/424, 425, 423; D3/294, 272, 273; 206/508, 511, 503, 518; 220/241, 242, 380, 675, 376, 334, 335, 337, 350, 354, 355, 356
